(57) **CLAIM**

The ornamental design for a lint trap rectangular container, as shown and described.

DESCRIPTION

FIG. 1 is an upper perspective view of the lint trap rectangular container showing my design;

FIG. 2 is an end view thereof;

FIG. 3 is a side view thereof, the opposite side being a mirror image thereof;

FIG. 4 is an opposite end view thereof;

FIG. 5 is a top plan view thereof;

FIG. 6 is a bottom plan view thereof; and,

FIG. 7 is a cross-section view of FIG. 2, taken along line 7-7, thereof.

The broken lines showing of liquid in FIG. 7 is included for illustrating the environmental matter of the lint trap rectangular container, and forms no part of the claimed design. The following article can be installed between the clothes dryer and the exhaust vent to separate, and retain the lint from a stream of hot air emanating from clothes dryer.
